(57) **CLAIM**

The ornamental design for a hold-up tool for pop-up sprinkler risers, as shown and described.

DESCRIPTION

FIG. 1 is a top, right and front perspective view of a hold-up tool for pop-up sprinkler risers showing my new design, and including a broken line representation of the hold-up tool when in use holding up a pop-up sprinkler riser;

FIG. 2 is a top, right and front perspective view of the hold-up tool of FIG. 1 as seen without the broken like representation of the pop-up sprinkler;

FIG. 3 is a rear elevational view of the hold-up tool of FIG. 2;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line showing is for illustrative purposes only and forms no part of the claimed design.
